Primary Examiner — Susan Bennett Hattan*Assistant Examiner* — Leanne Was(74) *Attorney, Agent, or Firm* — Baker & Hostetler LLP(57) **CLAIM**

I claim the ornamental design for a gimbal, as shown and described.

DESCRIPTION

FIG. 1 is a perspective view of a gimbal, wherein the broken lines illustrate environment structure that is not part of the design;

FIG. 2 is a bottom plan view of the gimbal of FIG. 1;
FIG. 3 is a front elevation view of the gimbal of FIG. 1, wherein the broken lines illustrate environment structure that is not part of the design;

FIG. 4 is a rear elevation view of the gimbal of FIG. 1, wherein the broken lines illustrate environment structure that is not part of the design;

FIG. 5 is a left side elevation view of the gimbal of FIG. 1, wherein the broken lines illustrate environment structure that is not part of the design;

FIG. 6 is a right side elevation view of the gimbal of FIG. 1, wherein the broken lines illustrate environment structure that is not part of the design; and,

FIG. 7 is a perspective view of the gimbal of FIG. 1, wherein the broken lines illustrate environment structure, associated with a gimbal shroud and a trim ring and dome that surround part of the gimbal, that is not part of the design.

The design is the visual features of a gimbal shown in solid lines in the drawings.
